UNITED STATES PATENT OFFICE

ROBERT T. ROMINE, OF MOUNT CLEMENS, MICHIGAN

CAR-LOADING APPARATUS

Application filed February 2, 1927, Serial No. 165,378. Renewed December 11, 1929.

This invention relates to the loading of metal for shipment in freight cars, such, for example, as box cars, flat cars or gondolas, and especially concerns the handling, loading, packing and shipment of metal, particularly strip or bar metal.

The present invention is a continuation in part of the invention shown and described in my co-pending application Serial No. 10 137,867, filed September 27, 1926. In said application there is disclosed an apparatus and method for loading and packing metal for shipment in freight cars, an adaptation of the broad invention thereof being shown 15 by way of example in connection with the handling of sheet metal, such as finished sheet steel. In the present application, I have illustrated a way in which the principle of the invention in my previous application is applied particularly to the handling, loading and packing of strip or bar metal in freight cars for shipment. One of the important purposes of the invention is to enable metal, such as strip or bar steel, to be shipped or handled in relatively heavy units incapable of being manually lifted, in which the constituent parts of the pack or bundle will remain intact during transit, and in which the shocks, jolts and motions of the 20 car will not result in the pack breaking loose or otherwise shifting so as to cause substantial damage to the car; and wherein the units or packs, such as bundles weighing from five to ten tons, may be handled without necessitating the breaking up of the bundles and the separate handling of the constituent parts.

A further object of the invention is to provide an apparatus for binding, bracing or maintaining the constituent parts of the bundle or pack together against such movement as would prevent removal of the packs as units at their destination, which apparatus is relatively inexpensive to manufacture, capable of extensive re-use, interchangeable, and adapted for use with packs of varying sizes.

In the drawings:

Fig. 1 is a top plan view of the loading ap-

paratus of this invention showing the pack of bar or strip metal supported for shipment.

Fig. 2 is a side elevation of the construction disclosed in Fig. 1.

Fig. 3 is an end view of the pack showing generally the construction of one of the buttresses.

Fig. 4 is a view, similar to Fig. 3, with one of the buttresses and base members at the end of the pack removed.

Fig. 5 is a view, partly in section, similar to Fig. 4, showing the position of the members for additionally preventing upward movement of the binders relative to the pack and its base or pallet.

Fig. 6 is a fragmentary perspective view of the bars and connecting means therefor forming a part of the adjustable transverse binders.

Fig. 7 is a detail perspective view illustrating the unassembled parts of the pressure device.

Fig. 8 is a detail perspective view showing the unassembled parts for connecting together, in spaced relation, the frame members of Fig. 6.

Figs. 9 and 10 are detail perspectives of the longitudinally extending truss members.

Fig. 11 is a perspective view of a portion of a freight car showing two packs of metal with their respective binding or bracing apparatus in position for shipment on the floor of the car.

Fig. 12 is a perspective view showing the inside of a box car with a stack lifter elevating a bundle into position to be deposited upon the lift platform of an electric lift truck.

Before explaining in detail my invention and the method or mode of operation embodied therein, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is

not intended to limit the invention beyond the terms of the several claims hereto appended or the requirements of the prior art.

In the drawings wherein like numerals of reference indicate similar parts in the several views, A designates a pack or stack of bar or strip steel, B designates the freight car floor, and C the transverse supports or base members forming a supporting pallet positioned on the car floor for supporting the pack A. Each pack, in the present instance, is bound together into a unit by means of binders 20, these binders being adjustable and of substantially the same construction as those described in my co-pending application above referred to. These binders comprise parallel strips or sections 21 and 22 each having a series of longitudinally spaced holes or perforations 23, as illustrated in detail in Fig. 6. The parallel bars 21 and 22 are held together in operative relation by means of a bolt and nut construction illustrated in Fig. 8, which construction comprises a bolt 24, nut 25, and sleeve 26 which surrounds the shank of the bolt 24 and which is positioned between the opposite inner faces of the bars 21 and 22, the sleeve 26 serving the purpose of maintaining the bars in their proper spaced positions as indicated clearly in Fig. 6. In order to properly space the transverse binders from the wooden strips D extending about the pack A, and to apply to the pack through the medium of the strips D, sufficient pressure to bind the constituent parts of the pack together properly, a pressure device E is employed, such device comprising a plate 27 bent at opposite ends to form a yoke adapted to embrace opposite sides of any one of the frame members of the binder. The central web or portion 27^a of the yoke extends transversely across the inner side of the frame members 21 and 22 constituting a part of the transverse binders, and has centrally thereof a tapped hole 28 through which is threaded an adjusting screw 29. Interposed between the end of the adjusting screw 29 and the wood strips or members D, is a metal thrust plate 30, having a recess 31 drilled centrally thereof to receive and center the adjusting screw 29. Each thrust or bearing plate 30 is preferably provided with multiple projections 32 (Fig. 4), the outer faces thereof forming a gripping surface engageable with the wood member D. Pressure devices as indicated at E are equidistantly spaced about the top and side of the pack and act against each of the several wood strips D. The pressure devices herein described are substantially like those described in my co-pending application previously mentioned.

Where desirable, additional means may be used for resisting longitudinal displacement of the constituent parts of the pack due to shocks to which the cars are subjected, or due to the weaving movement of the bundle

in transit. In the present instance I have provided buttresses extending across the ends of the pack. These buttresses comprise vertical or upright angle bars or trusses 40, having right angle flanges 41 and 42, the flanges 42 serving to support the opposite ends of similarly shaped horizontally disposed angle bars or trusses 43, which may be of smaller cross sectional area than the angle bars 40, thereby reducing considerably the weight of the apparatus. The angle bars or truss members 43 each has a vertically extending flange 44 positioned back to back with the flanges 42 of the vertically extending angle bars or truss members 40, and an outwardly extending horizontal flange 45. The ends of the angle bars 43 may be secured to the vertically extending bars or truss members 40 by means of rivets 46, or in any other suitable manner. Interposed between the inner face of each end buttress or frame and the pack, are a series of wooden strips 47 which preferably extend at right angles to the horizontal angle bars 43. These wood strips 47 are preferably placed edge to edge as clearly illustrated in Figs. 1, 3 and 11, to form a continuous surface or inner face composed of vertically extending wood strips. These wood members 47 in conjunction with the skeleton frame 40-43 not only provide a relatively light construction, but also provide cushioning means of relatively soft material in intimate contact with the edges of the bars or strips of metal to protect the ends of the bars or strips against damage.

To prevent the relative movement of the transverse wood blocks C, constituting the base members or supports for the pack of metal A, and to tie these supporting members C together, thereby forming a unitary supporting pallet, I provide, preferably, a pair of longitudinally extending angle bars or truss members 60 and 65 at each side of the bundle. The angle bars 60 are comparatively long as compared with the angle bars 65. The purpose of providing angle bars of different lengths is hereinafter fully described.

Each of the comparatively long angle bars 60 (Fig. 9), is provided with a vertically extending flange 60^a having a plurality of holes 61 formed therein, and a horizontally extending flange 60^b likewise provided with a plurality of spaced holes or apertures 62. The horizontal flange 60^b is adapted to rest upon the top surface of the wooden supporting blocks C of the pallet and to be secured thereto, as by means of nails 63, or any other suitable means, which are inserted in the holes 62 formed therein. Each of the shorter angle bars or truss members 65, (Fig. 10), comprises a vertically extending flange 65^a having a plurality of spaced holes 66 formed therein, and a horizontal flange 65^b, which is likewise provided with spaced holes 67 which are also adapted to receive the

nails 63. The short angle bar 65 is provided at one end with a substantially rectangular plate or metal piece 68 which is fitted into the space formed by the flanges 65^a and 65^b, and welded to said flanges to form an integral part of the angle bar construction. The plate 68 is provided with a preferably centrally located hole 69, the purpose of which will be hereinafter described. Each of the 10 longitudinally extending angle bars or truss members 60 and 65 is provided at spaced intervals with an inwardly projecting steel plate or strip 70 (see Figs. 9 and 10). The plates or strips 70 are preferably connected 15 with the longitudinally extending members 60 and 65 by rivets or in any other suitable manner, so as to provide an integral structure.

In order to support or maintain the buttresses or end protectors in a vertical position and to hold their inner wooden faces 47 in intimate contact with the ends of the bars or strips of metal in the pack, metal straps or links 75 are provided. These straps 20 or links are each provided adjacent their opposite ends with holes which are adapted to receive bolts 76 for securing the straps to the flanges 41 of the vertical angle bars 40 of the buttresses and also to the vertical 25 flanges 60^a and 65^a of the longitudinally extending angle bars 60 and 65, respectively.

In order to adjustably connect the opposed ends of the angle bars 60 and 65 together and to permit their relative movement towards one another, a tie rod or bolt 80 is positioned at opposite sides of the bundle A and attached to the angle bars. One end 80^a of the tie rod is bent at right angles to it so as to engage any one of the holes 61 formed 30 in the flange 60^a of the angle bar 60. The opposite end 80^b of the tie rod is screw-threaded and is adapted to pass through the hole 69 formed in the end plate 68 of the angle bar 65 which is positioned at the side 35 of the pack at the opposite end thereof. A nut 81 is threaded upon the end 80^a of the tie rod and connects the same with the relatively long angle bar 60, whereas a nut 82 is threaded upon the end 80^b of the tie rod 40 and serves to connect that end with the short angle bar 65. The tie rods positioned at opposite sides of the pack, are identical. These tie rods 80 effect the longitudinal adjustment of the buttresses to cause their inner 45 faces, comprising the wood strips 47, to engage the ends of the constituent parts of the pack. The purpose of providing angle bars of different lengths as described, is to permit the use of a standard form and size of 50 binding apparatus upon stacks or bundles of strip or bar metal of widely varying lengths. It will be seen that if the bundle is considerably shorter than those illustrated in the accompanying drawings, requiring 55 relative adjustment of the apparatus, it is merely necessary to insert the ends 80^a of each tie rod 80 into the proper hole 61 of the angle bar 60 and to rotate the nut 82 drawing the threaded end 80^b of the tie rod toward the opposed end of the other angle 60 bar 65. In other words, the major adjustment is effected by positioning the end 80^a of the tie rod in the proper hole 61 formed in the vertical flange 60^a of the long angle bar 60, and the minor or more accurate adjustment of the parts is effected by the co-operation of the threaded end 80^b of the tie rod, and the nut 82. Therefore, it is only necessary to thread a small portion of the end 80^b of the tie rod thus maintaining the 65 cost of such rods at a minimum. If all of the angle bars were of the same length, such as the angle bars 65, it would be impossible, when using them in connection with long 70 packs or bundles of metal, for the angle bars 80 to span the space between and inter-connect the lateral wood members C of the pallet to form a rigid, unitary base. Moreover, if the angle bars were all long, as are the 75 bars 60, they would be incapable of use in connection with shorter packs or bundles of metal for the reason that their ends, instead of being properly spaced apart to allow their relative adjustment would overlap and it would be practically impossible to tie them 80 together properly to bind the constituent parts of the pack together. The use of short and long angle bars diagonally disposed overcomes the above difficulties.

The purpose of providing the strips or plates 70 which extend beneath opposite sides of the pack or bundle, is to prevent the angle bars 60 and 65 from being ripped loose from the lateral wood members of the pallet when forces acting upon the bundle 100 or pack move the ends of the constituent parts thereof against one of the buttresses tending to cause the bundle to move upwardly or bend in the middle, or to cause the upper ends of the buttresses to swing outwardly, 105 such movement exerting a strain or upward pull upon the angle bars 60 and 65 relative to the transverse pallet members C.

In assembling the pack or bundle of strip or bar metal, the transverse binders, indicated generally at 20, are placed about the pack, and then the transverse wood members C forming the pallet may be placed in position. Each buttress is connected with one of the long angle bars 60 at one side and with 110 a short angle bar 65 at the other, and the buttresses which are connected to the straps or links 75, are placed in position at the ends of the pack.

Before the tie rods 80 are connected with 115 the opposed ends of the longitudinally extending angle bars 60 and 65, the wood strips 47 are placed in position between the frame work of each buttress and the ends of the constituent parts of the pack, so as to form, when 120 125 130

the buttresses are tightened upon the ends of the pack, cushioning means between said buttresses and said pack ends. Thereafter, the tie rods 80 are connected with the angle bars as previously described, and by tightening said rods, the buttresses are bound against the opposite ends of the pack. After the necessary adjustment has been effected, 10 nails 63 (Figs. 2 and 4) are inserted in the holes 61 and 67 formed in the angle bars 60 and 65, respectively, and driven into the wood members C to firmly secure the angle bars to the wood members and to provide an integral pallet or supporting structure for the 15 bundle.

It will be seen, therefore that it is an important purpose of the end buttresses to maintain the pack of strip or bar metal upon its pallet or supporting structure, and to securely bind the constituent parts of the pack to the pallet so as to allow the pack and its binding and supporting means to move or float upon the car floor as a unit to compensate for shocks or the like to which the car is 25 subjected in transit.

What I claim is:

1. Apparatus for binding strip or bar metal in a pack on the floor of a freight car for shipment, comprising a series of wood members 30 extending beneath the pack, means at each side of the pack for securing said members together to form a unitary support, and buttresses extending across each end of the pack for resisting the longitudinal displacement 35 of the constituent parts of the pack, said buttresses and said securing means being connected together.

2. Apparatus for binding strip or bar metal in a pack on the floor of a freight car for 40 shipment, comprising a plurality of transverse base members, means extending longitudinally of the pack at each side thereof for securing said base members together, binders extending about the pack, buttresses extending 45 across each end of the pack for resisting longitudinal displacement of the constituent parts of the pack, said buttresses being connected with said securing means and said securing means having means projecting beneath the pack for maintaining the same in 50 predetermined relation to the pack.

3. Apparatus for loading strip or bar metal in a pack on the floor of a freight car for shipment, comprising a base positioned beneath 55 the pack, spaced binders extending transversely about the pack, members extending longitudinally of the pack secured to said base and having means extending beneath the pack to prevent upward movement thereof relative to the base, and buttresses extending 60 across each end of the pack for resisting longitudinal displacement of the constituent parts of the pack, said buttresses being detachably connected with said members.

4. In an apparatus for loading strip or

bar metal in a pack on the floor of a freight car for shipment, the combination of a plurality of base members, longitudinal bars at opposite sides of the pack for securing the base members together to form a unit, adjustable binding means extending about the pack transversely thereof, and buttresses extending across the ends of the pack for resisting longitudinal displacement of the constituent parts of the pack, said buttresses being detachably connected with said bars.

5. An apparatus for loading strip or bar metal in a pack on the floor of a freight car for shipment, in combination, base members, truss members extending longitudinally of the pack at opposite sides thereof and connected with the base members to form a unitary supporting structure, means extending inwardly from said truss members beneath opposite sides of the pack to prevent upward movement of the truss members relative to said base members, and buttresses extending across each end of the pack to prevent longitudinal displacement of the constituent parts of the pack, said buttresses and said truss members being inter-connected, the buttresses having wooden inner faces adapted to engage the ends of the constituent parts of the pack.

6. The combination with an apparatus for binding strip or bar metal in a pack on the floor of a freight car for shipment, of buttresses extending across each end of the pack for resisting longitudinal displacement of the constituent parts of the pack, said buttresses having inner faces of wood adapted to engage the ends of the pack, and comprising a skeleton angle iron frame.

7. The combination with an apparatus for binding strip or bar metal in a pack on the floor of a freight car for shipment, of base members for supporting the pack on the floor of the car, means for securing the base members together, means connected with the securing means for resisting the upward movement of the securing means relative to the pack, spaced binders extending transversely of the pack for maintaining the constituent parts of the pack together, and means extending across each end of the pack in engagement with the ends of the constituent parts thereof for preventing their longitudinal displacement.

8. Apparatus for binding strip or bar metal in a pack on the floor of a freight car for shipment, comprising base members, longitudinal members at each side of the pack for interconnecting said base members, binders extending transversely about the pack, means at opposite ends of the pack for restricting the longitudinal movement and displacement 120 of the constituent parts of the pack, and means for connecting the adjacent longitudinal members to adjust their relative positions.

9. Apparatus for binding strip or bar metal in a pack on the floor of a freight car 130

for shipment, comprising a base, angle bars mounted upon said base and extending longitudinally of the pack at opposite sides thereof, binders extending transversely about the pack, buttresses arranged at opposite ends of the pack for restricting the longitudinal movement of the constituent parts of the pack, and tie rods connecting the opposed ends of the longitudinally extending angle bars for 10 adjusting the relative positions of the buttresses.

10. An apparatus for binding a pack of strip or bar metal on the floor of a freight car for shipment comprising longitudinally 15 spaced transverse base members between the pack and the car floor and adapted to move as a unit relatively to said floor, angle bars extending along opposite sides of the pack and connected with the base members for forming a unitary pack supporting structure, means carried by said angle bars projecting beneath the pack on opposite sides thereof for resisting the upward movement of the angle bars relative to the pack and base members, 20 spaced binders extending about the pack transversely thereof for resisting lateral displacement of the strips or bars, and buttresses operatively connected with said longitudinal angle bars extending across each end 25 of the pack, said buttresses each comprising a skeleton frame of angle bar construction and an inner wood face in engagement with the ends of the constituent parts of the pack, said buttresses resisting the relative longitudinal 30 movement of the constituent parts of the pack.

11. Apparatus for loading a pack of metal, such as strip or bar metal or the like, on a car floor, comprising a unitary wood pallet beneath the pack, means for binding the pack 40 transversely thereof, and means extending over the end or ends of the pack for resisting relative longitudinal movement of the metal and held in fixed relation to said pallet, said pallet being free to move on the car floor 45 to compensate for shocks or the like to which the car is subjected in transit.

12. Apparatus for loading a pack of strip or bar metal on a car floor comprising a support for the pack free to move on the car 50 floor, binding means for the pack and including devices for exerting pressure against the pack to resist relative movement of the constituent parts, additional means for resisting longitudinal movement of the metal, and 55 means for maintaining said last mentioned means in substantially fixed relation to said support.

13. The herein-described method of loading strip or bar metal for shipment on the 60 floor of a freight car, consisting in binding the metal together in a pack with the pack supported on a wood pallet free to move on the car floor, and uniting said pallet and pack to hold the same together against relative move- 65 ment.

14. An apparatus of the class described, comprising pallet members positioned on the car floor for supporting a pack, means for securing said members together, means connected to the securing means for resisting relative longitudinal movement of the parts of the pack, and means for resisting upward movement of the securing means relative to the pack. 70

15. An apparatus of the class described, comprising pallet members positioned on the car floor for supporting a pack, a pair of members at each side of the pack for connecting said pallet members, means for relatively adjusting the members of each pair, 75 and means connected to said members for resisting relative movement of the pack and pallet members. 80

16. An apparatus of the class described, comprising transverse supporting members for a pack, a longitudinal member at each side of the pack connecting said supporting members together, and means connected to said longitudinal members for resisting relative longitudinal movement of the pack and supporting members. 85 90

17. In an apparatus of the class described, a series of transverse wood members for supporting a pack on the floor of a carrier, longitudinal members at opposite sides of the pack connecting said wood members together, upright buttresses at the ends of the pack, and means for connecting said buttresses to said longitudinal members at each side of the pack. 95

18. In an apparatus of the class described, a series of transverse wood members for supporting a pack on the floor of a carrier, longitudinal members at opposite sides of the pack connecting said wood members together, upright buttresses at the ends of the pack, and means for independently connecting each buttress to a longitudinal member at each side of the pack. 100 105

In testimony whereof I affix my signature.

ROBERT T. ROMINE.
